UNITED STATES PATENT OFFICE.

LEO AVISUS, OF NEW YORK, N. Y.

DESIGN FOR A FLAG OR EMBLEM.

51,195.

Specification for Design.

Patented Aug. 28, 1917.

Application filed July 11, 1917. Serial No. 179,998. Term of patent 3½ years.

To all whom it may concern:

Be it known that I, Léo Avisus, a citizen of the United States, residing at New York city, in the county of New York and State of New York, have invented a new, original, and ornamental Design for Flags or Emblems, of which the following is a specification, reference being had to the accompanying drawing, forming part thereof.

The figure is a plan view of a flag or emblem showing my new design.

I claim:

The ornamental design for a flag or emblem, as shown.

LEO AVISUS.
